UNITED STATES PATENT OFFICE.

ERNEST DOUGLASS, OF POMONA, CALIFORNIA.

CARTON-SEALING MACHINE.

1,283,479..

Specification of Letters Patent.

Patented Nov. 5, 1918.

Application filed January 31, 1916. Serial No. 75,461.

To all whom it may concern:

Be it known that I, ERNEST DOUGLASS, a citizen of the United States, residing at Pomona, in the county of Los Angeles and 5 State of California, have invented a new and useful Carton-Sealing Machine, of which the following is a specification.

My invention relates to the use of cartons which are used extensively for packing 10 canned goods, fruits, and other merchandise. These cartons are made up of coarse paste-board, or similar material, and are shipped to the packer in a flat or knocked-down condition, a large number of the cartons 15 being thus packed in a small space so that they can be easily and cheaply handled. When the carton is to be packed it is opened into its squared position, and the flaps on one end are folded over and sealed with a 20 suitable adhesive. The merchandise is then packed inside the carton. The flaps on the other end are then folded over and sealed, and the package is ready for shipment.

The principal object of my invention is 25 to provide a very cheap device which can be used to easily and quickly seal the ends of such cartons.

In the drawings, which are for illustrative purposes only:

30 Figure 1 is a side elevation of my invention.

Fig. 2 is an end elevation of the toggle and operating mechanism therefor.

35 Fig. 3 is a partial plan view of my invention.

Fig. 4 is a side view partly in section illustrating the gage bar lock.

In the form of my invention illustrated in the drawings, 11 is a column which is secured to base members 12 by means of a 40 cross tie 13 and by means of inner braces 14 and outer braces 15. Pivoted on the inner base members 12 by means of hinges 16 are two standards 17 and 18, these 45 standards each carrying a member 19 over which a socket 20 fits, this socket being secured on the member 19 by a set screw, or other suitable means. A head, or plate, 21 of sufficient size to fit loosely inside the end 50 of the cartons 22, is secured to the socket 20, various sizes of plates being provided to suit the various sizes of cartons used. Radius bars 23 are secured to the column 11, projecting out on either side thereof and 55 having a small piece of metal secured therein, this metal forming an inner stop, the

radius bars 23 being turned up at their outer end to form outer stops. Stirrups 24 are secured to the standards 17 and 18, these stirrups surrounding the radius bars 60 23, sliding freely thereon, and serving to limit the movement of the standards by striking against the stops on the radius bars. Stop blocks 25 are secured on either side of the column 11, these stops also assisting 65 in limiting the movement of the standards 17 and 18. Gage bars 26 are slidably mounted on the standards 17 and 18. Pivoted to the top of each gage bar is a catch 27, these catches engaging notches 28 cut in 70 the standards 17 and 18, the catches 27 being normally held in the notches 28 by springs 29. A head bar 31 is secured to the top of the column 11, and head bar braces 32 tend to brace the head bar 31 to 75 the column 11. Holes 33 are cut in either end of the head bar 31, and plungers 34 and 35 slide freely therein, the plungers 34 and 35 consisting of a round rod. Secured by means of cotter pins 36 on the upper end of 80 the plungers 34 and 35 are washers 37. Compression lifting springs 38 are placed about the plungers 34 and 35, pressing against the head bar 31 and against the underside of the washers 37. These springs 85 tend to lift the plungers into their raised position, as shown at 35 in Fig. 1. Pivoted on pins 40 which pass through the braces 32 are toggle levers 41, these toggle levers 90 being forked as shown in Fig. 2, and extending down on either side of the plungers. A toggle stop pin 43 is secured in each of the toggle levers 41, and a handle lever 44 is formed on the upper end thereof. Toggle links 45 are pivoted on short rivets 46 secured in the toggle levers 41, the lower end of the links 45 being pivoted on pins 47 which are secured in and which pass entirely through plungers 34 and 35. The lower end of each of the plungers 34 and 100 35 has a head 48 formed thereon, this head sliding freely in a cavity 49 formed in clamping plates 50, these clamping plates therefore having a limited up and down movement with relation to the respective 105 plungers 34 and 35. Washers 51 are secured by means of cotter pins 52 on the lower end of the plungers 34 and 35 above the clamping plates 50, and compression springs 53 are placed between the washers 51 and the upper end of the clamping plates 50, these compression springs tending to 110

hold the clamping plates in their lower position with relation to the plungers 34 and 35.

The method of operation is as follows:—

The operator pulls the standard 18 out to 5 the position shown in the drawings, and places the carton 22 over the plate 21, folding the flaps of the carton 22 down in place and applying a suitable adhesive thereto. The standard 18 is then thrown into a vertical 10 position, and the clamping plate 50 is forced down against the top of the carton by means of the handle 44, this handle 44 rotating the toggle lever 41 through a little over ninety degrees into the position shown at 15 "A" in Fig. 1, in which position the pins 40, the rivets 46, and the pins 47, are practically in a straight line, forming a toggle, so that the clamping plate 50 is securely locked in place. The spring 53 provides an elastic adjustment 20 for the clamping plate 50, so that different thicknesses of cartons may be used, without in any way interfering with the efficiency of the apparatus, and the method of securing the plate 50 to the lower end of 25 the plungers allows this plate to adjust itself in a suitable plane to suit variations in the thickness of the carton ends.

In practice four or more standards, similar to 18, are used, the operator placing the 30 carton on one of these standards, applying the adhesive thereto, and forcing the plate down to clamp the end of the carton, this carton being left while other cartons are being placed on the remaining heads. By the 35 time all the heads are filled, the first carton will be dry and the operator lifts up on the handle 44, breaking the toggle, and allows the spring 38 to force the plunger up to its upper position, thereby relieving the clamping pressure 40 between the plate 50 and the head 21, and allowing the standard 18 to fall out into its original position against the outer stop 27, in which position the carton can be readily removed, the remaining cartons 45 being removed in order in the same way. After the cartons are removed, they

are filled with whatever merchandise they are to contain, the top flaps are sealed over with a suitable adhesive, and the carton is turned up side down so that the weight of 50 the contents will seal the other end.

I claim as my invention:—

In a carton sealing machine, a fixed column; a transverse head bar carried by the column; inclined braces extended between 55 the head bar and the column; a standard hinged for swinging movement toward and away from the column; a first plate on the upper end of the standard; a plunger slideable in the head bar; a second plate co-operating with the first plate; means for securing the second plate to the plunger for limited movement longitudinally of the plunger; a spring carried by the plunger and co-operating with the second plate to limit the 60 backward movement thereof under the pressure; a lever including a handle, and bifurcations spanning the plunger, the bifurcations being pivoted to the braces; links having their upper ends located between the bifurcations, the upper ends of the links being pivoted to the bifurcations, and the lower ends of the links being pivoted to the plunger; a pin extended between the bifurcations and engaging the outer edges of the 65 links when the handle is swung downwardly; an abutment on the upper end of the plunger; and a compression spring about the plunger and engaged at its ends with the abutment and with the head bar, said 70 spring serving to lift the plunger until the second plate is spaced vertically from the inner edge of the first plate when the standard is swung inwardly and outwardly, thereby to prevent contact between a carton on 75 the first plate and the under surface of the second plate.

In testimony whereof I have hereunto set my hand at Los Angeles, California, this 21st day of January, 1916.

ERNEST DOUGLASS.
